UNITED STATES PATENT OFFICE.

KAZIMERAS LAPINSKAS, OF UNION CITY, CONNECTICUT.

UNDERSEA DESTROYER.

1,299,483.

specification of Letters Patent.

Patented Apr. 8, 1919.

Application filed October 3, 1918. Serial No. 256,650.

To all whom it may concern:

Be it known that I, KAZIMERAS LAPINSKAS, a citizen of Russia, residing at Union City, county of New Haven, and State of Connecticut, have invented certain new and useful Improvements in Undersea Destroyers, of which the following is a specification.

This invention relates to improvements in apparatus adapted to engage destructive devices with the hulls of ships and has as its special object the provision of a submersible boat adapted to convey an operator in such a manner that he may be enabled to attach a bomb to the hull of an enemy ship whereby it may be destroyed.

A further object is to provide means whereby the operator is enabled to manually cause attachment between the bomb and the hull at any desired point therealong, so that the more vulnerable parts of the ship may be damaged.

These and similar objects are attained by the novel construction and combination of parts hereinafter described and shown in the accompanying drawings, forming a material part of this disclosure, and in which:

Figure 1 is a side elevational view showing a conventional type of ship and indicating the operation of the invention.

Fig. 2 is a side elevational view of the submersible boat.

Fig. 3 is a horizontal sectional view taken substantially on the center line of the same.

Fig. 4 is an enlarged transverse sectional view taken on line 4—4 of Fig. 3, and

Fig. 5 is a perspective view showing a preferred form of the bomb used in connection with the boat.

Referring to the drawings, the numeral 10, designates a conventional type of a sea going ship provided with all the usual and necessary paraphernalia and mechanism for its propulsion and navigation.

The undersea boat, indicated generally by the numeral 15, is comprised of an ovoidal casing 16, having symmetrically rounded ends 17, the casing being provided with a ballast or weight 18, by which it is held in a normally upright position.

On the upper side of the casing is an opening 20, normally covered by a dome 21, having curved flanges 22, held in position

on the casing by a ring 23 secured by screws 24, the arrangement being such as to provide a water tight covering through which the operator may enter the boat.

Interior walls 25 extend downwardly from the opening 20, the same being bent to form a seat 26, which continues an element 27, forming a water tight compartment 28 for the operator, while rearward of the partition is another compartment 29 above the ballast 18, this compartment having a horizontal flooring 30, which extends to the rear end of the casing, and has positioned therein a pump 31, driven by a chain 32, trained over a gear on the motor 33.

Rearward of the chamber 29 is a vertical partition 34, divided into two portions by horizontal floorings 35 the upper portion 36 being adapted to contain water, as is a similar chamber 37 at the front of the boat, and enterable into these chambers are pipes, respectively 38 and 39, through which water may be passed from one to the other by action of the pump 31, thus affording means whereby the submersible boat may be tilted by changing the water in the compartments.

In the lower compartment 29, over the ballast 18, is a storage battery 38, leading to a switch and controlling device 39, in the chamber 28, by which the motor 40 may be energized, this motor drives the chain 41 and by it a propeller shaft 42, extending through the end of the boat and having attached to it a propeller 43, by which the boat is propelled through the water.

Energy from the storage battery 38 also passes through a controlling device 44, whereby the motor 33 may be energized when desired. The wall 45 of the chamber 28 is inclined forward so as to provide room for the operator. The chamber 46 is open to the water through the passages 47 and is adapted to contain a store of the bombs 50, which may be passed outward through the opening 47 by extending the arms of the operator through openings 48 formed in the sides of the casing, there being engaged with the edges of the openings 48, impervious flexible sleeve-like attachments 52 through which the hands 53 may pass, it being possible to enter the hands through the openings 47, and engage the bombs, to which are attached powerful magnets 51, adapted to

adhere to the metallic hull of the ship 10 at any point along its surface.

In operation, the casing being carried upon the deck of the mother ship, the operator may enter, after which the dome 21 is secured in position and the submersible lowered into the water.

The operator is then able, by the various electrical controls, to tilt the boat in any 10 desired direction and to operate the same, either backward or forward, maneuvering as usual until the boat has arrived below the hull of the ship to be destroyed, whereupon the arms are extended, a bomb extracted by 15 from the storage chamber and attached by the magnet 51 to the hull at a vulnerable point, the submersible then removing to a place of safety while it explodes.

Having thus described my invention and

set forth the manner of its construction and 20 use, what I claim as new and desire to secure by Letters Patent, is:—

In a device of the class described, the combination with a hollow submersible casing, having a plurality of water tight compartments formed therein, a plurality of bombs carried in one of said compartments, said bombs having magnets formed thereon, and impervious flexible sleeve-like attachments formed through the sides of said casing permitting an operator to manually extract one or more bombs from said compartment and attach the magnet formed thereon to the hull of an adjacent ship.

In testimony whereof I have affixed my 30 signature.

KAZIMERAS LAPINSKAS.
